CLAIM

The ornamental design of a seat of an all terrain vehicle, as shown and described.

DESCRIPTION

FIG. 1 is a perspective illustration, from the front and right side, of a first embodiment of a seat of the all terrain vehicle of our design;

FIG. 2 is a top view thereof;

FIG. 3 is a right side view thereof;

FIG. 4 is a left side view thereof;

FIG. 5 is a rear view thereof;

FIG. 6 is a front view thereof;

FIG. 7 is a perspective illustration, from the front and right side, of a second embodiment of a seat of the all terrain vehicle of our design;

FIG. 8 is a top view thereof;

FIG. 9 is a right side view thereof;

FIG. 10 is a left side view thereof;

FIG. 11 is a rear view thereof; and,

FIG. 12 is a front view thereof.

Throughout the various figures of the drawings, certain views are not provided. The omission of a particular view is intended to convey that the element(s) depicted is/are plain and unornamented in that omitted view.

Where included, broken lines showing environment or structure are for illustrative purposes only and form no part of the claimed design.
